CLAIM

The ornamental design for a digital multifunction device, as shown and described.

DESCRIPTION

FIG. 1 is a front view of a digital multifunction device showing my new design;

FIG. 2 is a rear view thereof;

FIG. 3 is a top plan view thereof;

FIG. 4 is a bottom plan view thereof;

FIG. 5 is a right side view thereof;

FIG. 6 is a left side view thereof; and,

FIG. 7 is a perspective view thereof.

The gray colored areas indicate a change in color appearance from the other areas of the claimed design. The broken lines shown in the drawings represent portions of the digital multifunction device that form no part of the claimed design.
